LETTER OPENER OR SIMILAR ARTICLE

Gregory S. Dolgorukov, Ferndale, Mich.

Application December 28, 1953, Serial No. 28,218

Term of patent 7 years

(Cl. D74—1)

To all whom it may concern:

Be it known that I, Gregory S. Dolgorukov, a citizen of the United States of America, residing in Ferndale, county of Oakland, and State of Michigan, have invented a new, original, and ornamental Design for a Letter Opener or Similar Article, of which the following is a specification, reference being had to the accompanying drawing, forming a part thereof.

Fig. 1 is a top plan view of a letter opener showing my new design;

Fig. 2 is a sectional view thereof taken on the line 2—2 of Fig. 1; and

Fig. 3 is a sectional view thereof taken on the line 3—3 of Fig. 1.

The bottom or underside of the letter opener presents a substantially similar appearance as the top thereof shown in Fig. 1.

I claim:

The ornamental design for a letter opener or similar article, substantially as shown and described.
